(57) CLAIM

The ornamental design for a spray dispenser case, substantially as shown and described in the attached drawings.

DESCRIPTION

FIG. 1 is an isometric view of the spray dispenser case, having a front, left-hand, and a top portion, showing my design;

FIG. 2 is a front plan view thereof;

FIG. 3 is a bottom plan view thereof;

FIG. 4 is a top plan view thereof; and,

FIG. 5 is a right side view thereof, the left side being a mirror image of that shown.

The broken line showing of environmental structure shown in FIG. 2 is for illustrative purposes only and forms no part of the claimed design.

The surface(s) or portion(s) of the article not shown in the drawing or described in the specification form(s) no part of the claimed design.
